Robert D. Knudt.

UNITED STATES PATENT OFFICE.

ORIS K. DUNBAR, OF CENTERVILLE, INDIANA.

HAY-RACK CLAMP.

1,097,011.

Specification of Letters Patent.

Patented May 19, 1914.

Application filed November 13, 1913. Serial No. 800,752.

To all whom it may concern:

Be it known that I, ORIS K. DUNBAR, a citizen of the United States, residing in Centerville, in the county of Wayne and 5 State of Indiana, have invented a new and useful Construction for Hay-Rack Clamps, of which the following is a full, clear, and comprehensive specification, being such as will enable others to make and use the same 10 with exactitude.

The object of my present invention, broadly speaking, is to produce a clamp which will be strong and durable in construction, neat in appearance, easily placed 15 in position, will occupy a minimum amount of space, light in weight, and which can be manufactured and sold at a comparatively low price.

More specifically stated, my object is to 20 provide a clamp, intended, more particularly for securing together various parts of hay racks, but at the same time being adapted for other purposes, with means whereby the various parts are made adjustable to meet various conditions.

Other objects and advantages of my invention will be made apparent in the course of the following specification.

One manner for carrying out my invention in a practical manner, and that which 30 I have found the most practical, is shown in the accompanying drawings, in which—

Figure 1 is a perspective view of one of my clamps in connection with portions of 35 the several members which it is adapted to secure together. Fig. 2 is an enlarged perspective view of one of my clamps alone. And Fig. 3 is a perspective view of a hay-rack showing the application of my invention thereto for securing certain of the 40 parts in position.

Similar indices denote like parts throughout the several views.

In order that the construction, the operation, and the advantages of my invention 45 may be better understood and appreciated I will now take up a detailed description thereof in which I will set forth the invention as comprehensively as I may.

50 Referring now to the drawings in detail: Letter A denotes the sills, of which there are two in this instance, and they extend the full length of the rack. Letter B denotes the lower beams, of which there are 55 four in this instance, they being spaced apart, and they extend across underneath

the sills A. Letter C denotes the upper cross beams, of which there are four in this instance; they are spaced apart, and they extend across above the sills A. Each one 60 of the upper cross beams is located directly above and extends parallel with the lower cross beams B. The cross beams C are longer than the cross beams B. Said parts A, B, and C are all old, and we are concerned 65 therewith only in showing the application of my invention, and said parts may be variously changed as desired.

My invention proper relates only to the means for securing together the members A, 70 B, and C at each of the intersections, said means being shown alone in Fig. 2. Each of the clamps comprises a relatively long inverted U-shaped yoke 1 having two spaced apart parallel sides connected at the top, 75 with the ends terminating in outwardly protruding flanges, said flanges being at right-angles to the sides and parallel with the central portion of the yoke. Formed through the sides of the yoke are the vertical slots z, the same being located opposite each other and near the flanges on the lower portions of the yoke. A bolt aperture is formed vertically through each of the flanges of the yoke 1, for the purpose hereinafter 80 mentioned.

Numerical 2 denotes a U-shaped link, having two sides parallel with each other and a central portion connecting the sides. Formed through the upper portion of each 90 of the sides of the link 2 are the vertical slots x. The link 2 is adapted to interlock with the yoke 1, with the central portion of the link in contact with the under side of the central portion of the yoke, as shown in 95 Fig. 2. The yoke 1 and the link 2 are both formed of suitable lengths of flat material, substantially as indicated.

Numerical 3 denotes a bolt adapted to be disposed across through the slots x; and 100 numeral 4 denotes a bolt adapted to be disposed across through the slots z.

Numerals 5 and 6 denote bolts, identical with each other, which extend down through the bolt-apertures in the flanges of the yoke. 105 Below said flanges the said bolts 5 and 6 pass through the two plates 7 and 8, with nuts 9 and 10 threaded on the lower ends of the respective bolts 5 and 6.

In assembling the parts in operative positions the yoke 1 and the link 2 are first coupled together, as in Fig. 2, the yoke 1 is then 110

placed astride the sill A. The plate 7 is then brought into contact with and extended across the lower edge of the sill, after which the lower cross beam B is brought up into contact with the plate 7, as in Fig. 2. Holes are now (or previously) formed through the beam B to receive the bolts 5 and 6, which are inserted down through the apertures in the flanges of the yoke, through the plate 7, and through the beam B. The plate 8 is then brought into contact with the lower face of the beam B with the bolts 5 and 6 extending therethrough. After the above arrangement the nuts 9 and 10 are run on the bolts 5 and 6 and tightened, by which the yoke is drawn down tightly upon the sill. The bolt 4 is next inserted through the slots α and through a corresponding aperture formed through the sill A. I next place the upper cross beam C between the sides of the link 2, with its lower edge resting on the central portion of the yoke 1, as in Fig. 1, where it is secured by the bolt 3 which passes through the slots α and through a corresponding aperture formed through the cross beam C. When assembled as set forth it is apparent that the three members A, B, and C are securely locked together, and that without materially weakening said members. It is also apparent that if for any reason the members A, B, and C should shrink or become loose for any reason, it will be very easy to compensate therefor by tightening the parts without disassembling the parts. It should also be observed that by reason of my construction I am able to provide the yokes and the links of a standard size adapted to operate in connection with various size members A, B and C, it being necessary only to employ bolts of suitable lengths, varying them to meet various conditions.

I desire that it be understood that the clamp herein shown is not to be limited to the construction herein shown, but it may be employed in various ways as desired; neither am I to be limited to the exact details of construction herein shown and described.

Having now fully shown and described my invention, what I claim and desire to secure by Letters Patent of the United States, is—

1. A clamp comprising a yoke having parallel sides spaced apart and a flange extending out from each end of the yoke, a link engaging directly with the central portion of the yoke, bolts extending downward from said flanges of the yoke, a bolt extending across through vertical slots formed through the sides of the yoke, and a bolt extending across through the sides of the link, all substantially as shown and described. 55

2. A clamp comprising a yoke formed of flat material having parallel sides spaced apart and a central portion connecting said sides at the top, there being a flange extending out from each end of the yoke at the lower portion thereof, a bolt connecting the sides of the yoke and disposed through vertical slots formed through the sides of the yoke, a link formed of flat material and having two parallel sides and a central portion adapted to engage under the central portion of the yoke, a bolt disposed across through apertures formed through the sides of the link, and bolts extending down through apertures formed through the said flanges of the yoke. 60 70 75

3. A clamp comprising a yoke having parallel sides spaced apart and having vertical slots formed in its sides, a flange extending out from each end of the yoke, a link whose central portion is adapted to engage with the central portion of the yoke, securing means for each of said flanges, securing means extending across through said slots in the sides of the yoke, and securing means extending across through the sides of the link, all substantially as shown and described. 80 85 90

In testimony whereof I have hereunto subscribed my name to this specification in the presence of two subscribing witnesses.

ORIS K. DUNBAR.
